(57) **CLAIM**

The ornamental design for a screen protector hanger bracket, as shown and described.

DESCRIPTION

FIG. 1 is a front perspective view of a screen protector hanger bracket, showing my new design;

FIG. 2 is a rear perspective view thereof;

FIG. 3 is a front view thereof;

FIG. 4 is a rear view thereof;

FIG. 5 is an enlarged left side view thereof;

FIG. 6 is an enlarged right side view thereof;

FIG. 7 is a top view thereof;

FIG. 8 is a bottom view thereof;

FIG. 9 is a bottom view showing the screen protector hanger bracket in a use state;

FIG. 10 is a top view showing the screen protector hanger bracket in a use state;

FIG. 11 is an enlarged detail view of area 11 in FIG. 2; and,

FIG. 12 is an enlarged detail view of area 12 in FIG. 8.

The broken lines in the drawings illustrate the portions of the screen protector hanger bracket, which form no part of the claimed design.

The dash-dot-dash broken lines encircling the enlarged views are for annotative purposes only and form no part of the claim thereof.

1 Claim, 12 Drawing Sheets
